ROAD PAVER

Clyde G. Abernathy, Hornell, and Axel E.
Lundbye, Nunda, N. Y.

Application December 15, 1936, Serial No. 115,976

18 Claims. (Cl. 94—44)

This invention relates to a road paver and more particularly to a machine for laying and grading stone and asphalt mixes upon roadways and resurfacing the same or in providing an original surface or base for the road. The machine can be used for laying and grading either cold mixes or stone, asphalt and solvent for the asphalt or hot mixes of asphalt and aggregate.

In laying and grading asphalt and stone materials on a roadway considerable difficulty has been encountered by reason of the fact that the stone and asphalt mix is extremely heavy and difficult to handle and lay to an accurate surface. It is the principal object of this invention to provide a machine which lays and grades heavy mixes of asphalt and stone, or the like; which will handle large quantities of such mixes and rapidly and accurately grade the same to provide the smooth and uniform surface desired; and which accomplishes this without requiring any handling of the mix, the mix being dumped directly into the hopper of the machine from the trucks used for transporting the mix to the job.

The present invention is an improvement on the paver shown and described in the Clyde G. Abernathy Patent No. 1,994,082, dated March 12, 1935, and also shown in the copending application of Clyde G. Abernathy, Ser. No. 744,933, filed April 21, 1934. In the paver forming the subject of both the present application and the said Abernathy patent and application the paver consists generally of a frame having front steering wheels which ride along the surface to be paved, rear rollers or wheels which ride upon the surface laid by the machine, a hopper disposed at the center of the carriage between the front and rear wheels and a horizontally reciprocating toothed cutter bar which cuts off the column of paving material being discharged from the hopper. This cutter bar is located below the hopper and therefore it grades the road along a line determined by the differential in height between the front and rear wheels of the paver so that a substantially smooth pavement is laid even though the front wheels are riding over an extremely rough and irregular subgrade. The smoothness of the finished roadway is further increased by the usual practice of laying the roadway in two layers, the finishing of the final layer by the machine providing a specially smooth and uniform roadway. With such a paver all necessity for the use of forms and the like is eliminated.

In addition to the objects set forth in the said Abernathy patent and application, the present

application is directed to the following separate improvements:

A further object of the present invention is to provide a simple and convenient means for independently adjusting each of the front steering wheels vertically relative to the carriage and hopper carried thereby. By this means a rough adjustment of the thickness of the layer being laid can be obtained and also the height of the two wheels can be independently adjusted to meet different conditions encountered on a roadway, such as a highly crowned subgrade on which it is desired to lay a slightly crowned surface, it being understood that the roadways are generally laid in parallel strips.

Another object of the present invention is to provide a simple and convenient means for adjusting the curvature of the reciprocating cutter bar from the operator's platform to obtain any desired crown of the road.

Another purpose of the present invention is to provide a quick lift for the cutter bar which permits the cutter bar to be quickly released and elevated and as quickly returned to its initial position. It frequently happens in paving a road that an intersecting paved road is encountered. The quick lift for the cutter bar permits of quickly lifting the cutter bar after which the paver can be transported to the other side of the intersecting road; the cutter bar replaced to its initial position and the paving continued. It will also be understood that this quick release permits of quickly elevating the reciprocating cutter bar if an obstruction should be encountered.

Another aim of the present invention is to provide a simple and effective means for heating the reciprocating cutter bar, such heating insuring the smooth operation of the cutter bar in cutting through the column of hot mix and also in perfecting its action in ironing the surface of the roadway being laid. The heat for this purpose is preferably derived from the exhaust gases of the gas engine which is used for driving the paver and reciprocating the cutter bar, but it will also be understood that the hot water developed in the cooling system of the gas engine might also be employed and also that the heat might be applied from a separate heating device such as a torch or the like.

Another purpose of the present invention is to provide an indicator in the form of a bubble level which indicates the tilt or list of the paver carriage. The purpose of such a bubble level is to facilitate the laying of a crowned roadway.

in a plurality of parallel strips. Thus, in laying a strip along one side of a crowned roadway the front wheels are set to maintain the desired list and the bubble indicator is set so that its bubble 5 is centered at this list. Any departure from this desired list, of course, immediately shows on the bubble indicator and the proper adjustment to compensate can be made.

Another object of the present invention is to 10 provide a simple and effective means for applying lubricant to the rear rollers so that there is no danger of any of the freshly laid roadway sticking to the rollers.

Another purpose of the present invention is 15 to provide a dolly which can be used to support either end of the cutter bar. This dolly is provided with a pair of rollers which are extended to ride upon a strip of paving material already laid and which serve as a gage with the corresponding 20 end of the cutter bar, thereby to insure a smooth and uniform joint between the two strips. It will further be seen that by the use of such a dolly, plus the level indicator, the gaging of the strip of roadway being laid can be gaged exclusively from the strip of pavement already laid and on the edge of which the dolly rides, since any departure from the proper list of the paver 25 in laying the second strip will be immediately detected on the bubble level.

30 Another object of the invention is to provide a paver having a simple means for blocking off any desired portion of the hopper so that the paver will lay a strip of less than the maximum width, this blocking off means being quickly 35 inserted in the hopper and also quickly removed.

Another object of the invention is to provide 40 a paver having a vertically adjustable reciprocating cutter bar which determines the grade and which is spring supported to permit it to yield slightly in a vertical direction on encountering large obstacles and in which a gage is provided which is connected to the cutter bar adjusting mechanism above the spring support so that such minor accidental fluctuations in the 45 elevation of the cutter bar which are compensated by the springs do not register on the gage.

Another object of the invention is to provide 50 a simple and effective means of adjusting the height of the cutter bar and which include means for adjusting the tension of the above spring support for the same as set forth above.

Another object of the present invention is to 55 provide a simple and convenient means for providing any desired crown in the cutter bar so that the surface laid has the desired crown. These adjusting means are rendered conveniently operable from the operator's platform and are preferably actuated from a single hand wheel which operates a cam shaft so formed and connected with the cutter bar assembly as to provide 60 any desired crown in the road on turning the hand wheel. Preferably an indicator is also provided so that the operator can observe at any time the crown to which the cutter bar is set to provide.

Another purpose is to provide means operable 65 from the same hand wheel which adjusts the crown of the cutter bar for adjusting the crown of the group of tampers which follow the cutter bar, thereby providing a single adjustment for the crown of the cutter bar and the tampers and avoiding irregular tamping.

Another purpose of the present invention is to 70 provide a simple and efficient scarifier for rough-

ening the paved surface laid by the paver preparatory to its being subsequently rolled.

Other objects of the present invention will appear from the following detailed description.

In the accompanying drawings the paver is 5 shown after having been stripped of a number of details forming no part of the present invention, reference being made to the said Abernathy Patent No. 1,994,082 for a complete showing of such details.

Fig. 1 is a top plan view of the paver embodying our invention.

Fig. 2 is a fragmentary vertical longitudinal section, taken on line 2—2, Fig. 1 and showing the level indicator.

Fig. 3 is a front elevation, looking forwardly of the level indicator shown in Fig. 2.

Fig. 4 is a side elevation of the paver.

Fig. 5 is a fragmentary view, similar to Fig. 4, and showing the cutter bar supported at one 20 end by a dolly which in turn is supported on the edge of a strip of pavement already laid.

Fig. 6 is a vertical fragmentary section, taken on line 6—6, Fig. 5.

Fig. 7 is a rear elevation of the paver.

Fig. 8 is a fragmentary vertical fore and aft section taken on line 8—8, Fig. 7 and showing the roller mounting for the sub-carriage which carries the scarifier.

Fig. 9 is a vertical fragmentary fore and aft 30 section taken on line 9—9 of Fig. 7 and showing a part of the drive mechanism for reciprocating the scarifier subcarriage.

Fig. 10 is a horizontal fragmentary section taken on line 10—10; Fig. 7 and looking downwardly upon the scarifier.

Fig. 11 is a vertical fragmentary section on an enlarged scale through the adjustable pintle which supports each front wheel for steering movement, this view showing the means for adjusting each steering wheel vertically.

Fig. 12 is a horizontal section taken on line 12—12, Fig. 11.

Fig. 13 is a vertical fragmentary fore and aft section taken on line 13—13, Fig. 1, and showing 45 the quick-lift device for quickly elevating the cutter bar out of operative position and returning it to the same position.

Fig. 14 is a vertical fragmentary section taken on line 14—14, Fig. 13.

Fig. 15 is a transverse section through the 50 road paver showing the means for adjusting the curvature of the reciprocating cutter bar by a single adjusting wheel located on the platform.

Fig. 16 is a transverse section through the 55 paver taken somewhat to the rear of the section forming Fig. 15 and showing the tampers which tamp the roadway after having been graded by the cutter bar.

Fig. 17 is an enlarged fore and aft section 60 taken generally along line 17—17, Fig. 16 and showing the manner in which the tampers are reciprocated and also showing the manner in which the curvature of the line of tampers is adjusted to conform to the curvature to which 65 the cutter bar was adjusted.

Figs. 18 and 19 are diagrammatic views showing the manner in which the cams which adjust the curvature of the cutter bar turn in unison to effect any desired curvature thereof, Fig. 70 18 showing the position of the cams when the cutter bar is crowned and Fig. 19 showing the position of the cams when the cutter bar is straight.

Fig. 20 is a view similar to Fig. 19 showing 75

another arrangement in which cams of different throws are employed to effect the adjustment of the curvature of the cutter bar.

Fig. 21 is a section taken on line 21—21, Fig. 5 17 and showing the individual construction of the several tampers.

Fig. 22 is a view similar to Figs. 15 and 16 of the tamping mechanism, a part being shown broken away, and showing a modified form of 10 the means for adjusting the curvature of the cutter bar and also the curvature of the tampers.

Fig. 23 is a fragmentary enlarged view of the 15 adjusting means shown in Fig. 22.

Fig. 24 is a fragmentary vertical fore and aft 20 section taken on line 24—24, Fig. 22.

Fig. 25 is a vertical section, taken along line 25—25, Fig. 22.

Fig. 26 is a vertical fore and aft fragmentary 25 section through the roller which contacts with 20 and oils the main roller of the paver, this section being taken on line 26—26, Fig. 7.

Fig. 27 is a vertical transverse section, taken 25 on line 27—27, Fig. 26.

Fig. 28 is a fragmentary perspective view of the 30 cutter bar assembly.

The main frame of the carriage is shown as 35 being composed of channel beams, each side including two channel beams 30 and 31 which are brought together at their forward ends to form supports for the steering wheels, and cross beams 32 and 33 connecting these side beams. The cross beam 32 connects the rear ends of all of the side beams 30 and 31 and the cross beam 33 is arranged adjacent the center of the carriage 35 and cross connects the inner channels 31.

The rear end of the carriage or frame is supported by a pair of rollers 34 and 35 which are arranged to ride upon the surface freshly laid by the machine and each roller is independently 40 supported at its opposite ends in yielding bearings provided at the lower ends of brackets 36 which project downwardly from the frame of the carriage, the bearings permitting the rollers to adapt themselves to the crown of the road. The 45 front end of the machine is supported by a pair of steering wheels 37 and 38 which are adapted to ride upon the subgrade or surface which is to be paved.

Between the front steering wheels and the 50 rear rollers is disposed a hopper 40 having side walls 41 and 42, a rear wall 43 which is preferably vertically disposed and a front wall 44 which is disposed at an angle, the front end thereof being comparatively low and being supported 55 by an angle bar 45. The rear end of this front wall 44 is supported by an angle bar 46 and terminates in an elongated opening 47 which extends the full width of the hopper between the rear end of the front wall 44 and the bottom 60 of the rear wall 43. Through this opening 47 the material is discharged onto the subgrade being surfaced.

The paver is propelled by a gas engine 50 which is mounted upon the operator's platform 48. This 65 gas engine drives, through gearing contained in a gear box 51, a transmission contained in a transmission housing 52. The transmission contained in the housing 52 drives a chain 54 (Fig. 7) which chain in turn drives a sprocket 55 on 70 a countershaft 56. This countershaft has fixed thereto a pair of sprockets which drive chains 57, these chains driving sprockets fast to the separate axles 58, 58, one axle being provided for each roller 34 and 35. The independent axles 75 of the two rollers 34 and 35 are shown as being

mounted at each end in bearing blocks 69 each of which is slidably mounted in vertical slide-ways provided in each bracket 36 sufficiently loosely to permit tilting of the axles 58, 58 and thereby permit the rollers 34, 35 to independently adapt themselves to the crown of the road. Each bearing block 68 is supported by a compression spring 69, the pressure of each spring being independently adjustable in any suitable manner as by the adjusting screw shown in Fig. 10 7. While each axle 58 is shown as being supported at each end in the spring backed bearing block 58, such blocks are only essential at the inner or adjacent ends of the axles 58, 58 to 15 permit the inner ends of the rollers 34, 35 to move upwardly or downwardly and adapt themselves to the crown of the road being laid.

It will be understood that the transmission contained within the housing 52 is under suitable manual control so that the gas engine can be 20 connected to propel the paver or be disconnected therefrom at will. Such control levers are completely illustrated in the said Abernathy application Ser. No. 744,933, but inasmuch as this control forms no part of the present invention it is not illustrated in the present application. 25

The gas engine 50 also rotates a raker bar 59 as the paver travels, this raker bar 59 serving to mix the material in the hopper 40 and insure 30 its free passage through the slot 47 in the bottom of the hopper and also serves to spread the material uniformly along the hopper, the materials being dumped into the hopper directly from the truck. For this purpose the raker bar 35 includes a shaft 60 which is square in cross section at its center and its ends are journaled in bearings at the side walls 41 and 42 of the hopper. A plurality of L-shaped blades 61 are mounted on the square faces of the raker bar shaft, 40 these blades being capable of adjustment as to angularity so as to vary their spreading action in accordance with the particular material being handled, as more fully set forth in the said Abernathy application. The drive for the raker bar 45 includes a pinion 62 mounted on the transverse drive shaft 53 which is driven by the gas engine, as previously described. This pinion 62 meshes with a gear 63 which is fast to a jack shaft 64, this jack shaft being journaled in a suitable 50 bracket 65 carried by the main frame. This jack shaft also carries a sprocket which drives a chain 66, this chain driving a sprocket 67 fast to the raker bar shaft 60.

Each of the front steering wheels 37 and 38 55 is adjustable as to height independently of the other. For this purpose the ends of each pair of side channels 30 and 31 are welded to a steering bearing 70 which carries the steering spindle 71. This spindle is fixedly secured to a steering 60 knuckle 72 in any suitable manner and the lower end of this knuckle carries the stub axle 73 of the corresponding steering wheel 37 or 38. A steering arm 74 projects laterally outward from each steering knuckle and is connected to a drag 65 link 75. The other end of each of these drag links 75 is connected to an arm 76 the two arms 76 being fast to a cross shaft 77, this cross shaft being suitably journaled in the main frame and extending underneath the lower wall 44 of the 70 hopper. On this shaft is mounted a worm wheel 78 which is driven by a worm 79 on the steering shaft 80. The steering shaft 80 extends up to the drivers' platform 48 and is driven by the usual steering wheel 81. 75

To independently adjust each steering wheel vertically, the spindle 71 of each steering wheel is provided with a series of spaced annular grooves 82. Each of these grooves is adapted to receive a horseshoe shaped washer 83. These horseshoe shaped washers support the bearings 10 and it will therefore be seen that by selecting the groove 82 in which the horseshoe shaped washer is inserted the height at which the corresponding side 10 of the frame of the paver is supported by each steering wheel can be adjusted. The purpose of providing this adjustment is to provide a rough adjustment for the thickness of the layer deposited through the hopper and also to permit 15 of adjusting the entire carriage to any desired angularity or list as conditions may require. Thus, if it is desired to resurface a highly crowned road with a pavement having a smaller crown and it is necessary to build up the roadway in 20 parallel strips the front wheel nearest the curb is adjusted so that that side of the carriage is elevated relative to the side of the carriage nearest to the center of the road. By this means it will be seen that more material can be layed to the 25 curb by raising the front wheel on one side.

25 The hopper 40 is not, of course, of sufficient size to take an entire load from the trucks which transport the material to the job. In order to facilitate the discharge of the material from the
30 truck into the paver the truck is backed up between the front wheels of the paver and until its rear wheels engage rollers 84 mounted on the angle bars 45 of the hopper. As the paver moves along the paver pushes the truck forward, the
35 truck gradually emptying the mix into the hopper. The truck wheels, of course, rotate as the truck is pushed along and as the rollers 84 will rotate with the truck wheels it will be seen that these rollers provide a rolling drive between the
40 paver and the truck. When the truck has been completely discharged, it is driven away and another truck brought up against the rollers 84. This provides an extremely simple means for handling the problem of keeping material in the
45 hopper.

The hopper 40 is provided with a power cutoff or closure which closes the slot 47 in the bottom of the hopper when desired. The purpose of such a power cutoff is to permit of transporting the paver over areas which are not to be paved. Thus, if an intersecting paved road is encountered, the operator paves up to the intersecting road, closes the power cutoff so as to close the opening of the bottom of the hopper, drives the paver across the intersecting roadway, opens the power cutoff and continues paving the roadway. This power cutoff includes a plate 87 which extends the full width of the hopper and is slidably mounted under the lower wall 44 so as to be movable under the discharge slot 47 of the hopper and close this slot. The support for this plate can be of any suitable form. To this closure plate 87 is secured a rack 88 which is driven by a gear 89. This gear is mounted on a shaft which is driven by a bevel gear 90, this bevel gear being driven by a pinion 91 on an angular shaft 92. This shaft is driven by a manually operable clutch (not shown) for the jack shaft. It will also be seen that this power cutoff can be used to clear the path for the paver under certain conditions. Thus, if the supplying truck should accidentally drop a large mass of the paving material on the road in front of the hopper, this would ordinarily have

to be leveled off by hand to prevent the paver from becoming stuck. However, it will be seen that the provision of the power cutoff avoids the necessity of so doing since the operator can move the hopper up to the obstructing mass and then close and open the power cutoff, the plate 87 operating as a leveler and cutting down the obstructing mass on the advance of the paver to permit the hopper to pass thereover. 5

It is frequently desirable to lay a strip of pavement less than the full width of the hopper. To do this it is necessary to block off a portion of the hopper. The means for so blocking off portions of the hopper include a series of narrow plates 93 having holes at their opposite ends, these plates fitting over a series of pins 94 provided in the bottom of the hopper along the discharge slot 47. These series of pins extend inwardly from opposite sides of the hopper to a point providing the narrowest strip which would be desirable to lay, no pins being necessary for a substantial distance from opposite sides of the center of the hopper. The innermost of the plate or plates 93 preferably has attached thereto an edger plate 95 which extends forwardly under the front wall 44 of the hopper and also rearwardly under the cutter bar 100, hereinafter described, the purpose of this edger plate 95 being to secure or mold a square shoulder at the edge of the strip being laid.

The material being discharged from the hopper is cut to an accurate grade by a toothed cutter bar 100, the teeth of which project forwardly under the opening 47 of the hopper so that the cutter bar cuts into the column of material being deposited from the hopper. This cutter bar is reciprocated; the opposite ends thereof are independently adjustable as to height so as to be adjustable to meet any conditions encountered; it is capable of being curved to provide any desired crown in the surface finished by it; is provided with a quick release so that it can be quickly elevated and replaced to its original position in, for example, crossing an intersecting paved road; and is also heated so as to facilitate its cutting through the mix and also to provide an ironing action.

The cutter bar includes a channel 101, as best shown in Figs. 13 and 14, which is not only set flat but also is provided with a series of slots in its flanges, as best shown in Fig. 15, so that it can be flexed vertically. To the bottom of this channel are welded a pair of strips 102, and to the bottom of these strips are secured, in any suitable manner, a series of cutting plates 103 which project forwardly and have their front ends pointed so as to form the teeth of the cutter bar. These plates are, of course, rendered removable so that they can be replaced as they wear and these teeth project forwardly under the rear wall 43 of the hopper so as to cut into the column of material being discharged from the hopper.

The cutter bar structure which is described 65 is reciprocated along a track 104, the curvature of which can be adjusted. The connection between the cutter bar and the track 104 includes a plurality of bearing brackets 105 which, as best shown in Figs. 13-15, are rigidly secured at spaced 70 intervals to the upper face of the channel 101 and each of which carries a pair of rollers 106 and 107 which engage the upper and lower sides, respectively, of the track 104. The cutter bar is reciprocated in any suitable manner, as by a 75

link 108 which can be reciprocated by the gas engine 50 in any suitable manner, such as is shown in the said Abernathy patent. The teeth of the cutter bar structure extend completely 5 to the end of the channel 101 and are projected beyond the sides of the hopper as the cutter bar is reciprocated. By this means, in laying a strip of paving material against a strip which has already been laid, the material being laid is worked 10 into the edge of the strip already laid and a homogeneous seamless joint is produced.

The track 104 for the cutter bar is supported at its ends on brackets 109 which are secured 15 to the underside of an angle bar 110. This angle bar extends the full width of the paver and at each end is held against rearward movement by a link 111 which links are pivotally connected to the front lower corners of the side plates 41 and 42 of the hopper. These links take the rearward thrust of the cutter bar in moving forwardly and cutting off the column of material being discharged by the hopper. To permit of independently raising or lowering either end of 20 the cutter bar assembly an angular bracket 112 is secured to each end of the angle bar 110 and the adjusting mechanism is secured to this angular bracket 112. Each adjusting mechanism includes a bracket 113, the two brackets being 25 connected to the carriage or frame of the paver by a common quick-lift device indicated generally at 114. The quick-lift device includes a cross shaft 115 which is suitably journaled in brackets 116 on the cross channel 33 and at each end has 30 a crank lever 117, the crank pin of which is in the form of a cap screw 118 which connects the free end of the crank lever with the corresponding bracket 113, as best shown in Figs. 13 and 14. A segmental ratchet wheel 119 is fast to the cross shaft 115 and is engaged by the tooth 120 of a 35 detent 121. This detent 121 is pivoted, as at 122, to one of the brackets 116 and is normally pressed upwardly and into engagement with the ratchet wheel 119 by a small compression spring 123. The free end of the detent 121 is extended to form 40 a foot treadle 124.

Another bracket 125 is secured to the cross beam 33 adjacent the ratchet wheel 119 and carries a swinging hand lever 126. This hand lever 45 carries a pivoted pawl 127, the free end of which is formed to provide a tooth which engages the teeth of the ratchet wheel 119 and the other end of which is connected to a rod 128 which is lifted against the resistance of a spring 129 by a small 50 L-shaped lever 130 pivoted to the upper end of the hand lever 126 adjacent the grip of the hand lever 126. The spring 129 normally holds the pawl 127 out of engagement with teeth of the ratchet wheel 119 and when both the hand lever 55 126 and the small lever 130 are gripped so as to move the small lever 130 toward the grip of the hand lever 126 the rod 128 is elevated so as to throw the tooth of the pawl 127 into engagement with the teeth of the ratchet wheel 119.

60 The majority of the teeth of the ratchet wheel 119 are of regular ratchet form but these teeth terminate in a special locking recess 131. This locking recess has parallel sides extending substantially in a radial direction and the tooth 120 of the detent 121 is similarly shaped to have parallel sides and exactly fit the recess 131. Therefore, when the tooth 120 is engaged in the recess 131 the ratchet wheel is locked against rotation in either direction. In order, therefore, to lift 65 the cutter bar from its, say, operative position

by the quick release device it is first necessary for the operator to step on the treadle 124 so as to withdraw the tooth 120 from the locking recess 131. Upon then gripping both the grip of the lever 126 and the small L-shaped lever 130 the small lever 130 is moved so as to depress the rod 128 against the resistance of the spring 129 and throw the dog or pawl 127 into engagement with the teeth of the ratchet wheel 119. Upon then swinging the hand lever 126 rearwardly the ratchet wheel 119 is rotated and the operator thereupon releases the foot treadle 124 so that the spring 123 moves the detent 121 so that its tooth engages one of the ratchet teeth of the ratchet wheel 119. It will be seen that in 15 the continued elevation of the cutter bar assembly the detent 121 acts in the manner of an ordinary detent and that by reciprocating the hand lever 126 and pressing upon the small L-shaped lever 130 on each backward stroke and releasing 20 it on the forward stroke the ratchet wheel is turned and held in any turned position. The turning of the ratchet wheel of course rotates the cross shaft 115 and its crank arms 117 elevate the brackets 113 thereby lifting the angle 25 bar 111 and the track and cutter bar assembly carried thereby. It will be seen that by reversing the operation of the pawl and detent 127, 121, the cutter bar assembly can be lowered to any 30 desired position.

In order to prevent accidental operation of the quick release through the operator inadvertently stepping on the treadle 124, a locking device is provided which, as best shown in Fig. 13, consists of a sliding plate 132 slidingly secured to 35 the main frame by bolts 133 and carrying a screw 134. The plate is so arranged that when the quick-lift is raised the operator can kick the plate 132 under the treadle 124, the screw 134 then preventing the treadle from being accidentally depressed. The screw, of course, provides an 40 adjustable stop.

Each of the brackets 113 carries an adjusting mechanism by which the corresponding end of the cutter bar assembly can be adjusted vertically relatively to the carriage. For this purpose the bracket is provided with an upper arm 135, an intermediate arm 136 and a lower arm 137, as best shown in Fig. 14. In the upper arm is threaded a vertical screw shaft 138 which is 45 turned by a hand wheel 139. The lower end of the screw shaft 138 is rotatably secured to a vertically movable slide block 140 so that upon turning the hand wheel 139 this block is elevated or depressed. This block is guided in the bracket 50 113 and preferably suitable graduations, as indicated in Fig. 4, are provided to indicate the relative position between the bracket 113 and the block 140. To the sliding block 140 is also connected a vertical rod 141 upon which the corresponding end of the cutter bar assembly is hung. This rod is preferably screwed into the block 140 and held in position by a lock nut and its lower end extends through the top of the bracket 112. A head 142 is provided at the lower end of this 55 rod 141 and a relatively small compression spring 143 is interposed between this head and the underside of the bracket 112. A sleeve 144 surrounds the intermediate part of the hanger rod 141 and is guided by the intermediate and 60 lower arms 136, 137 of the bracket 113. A rotatable hand wheel 145 is mounted on the upper threaded end of the hanger rod 141 and is adapted to engage the upper end of the sleeve 144. The lower end of this sleeve bears against a col- 65 70 75 75

lar 146 which in turn bears against a compression spring 147 interposed between it and the upper side of the bracket 112.

It will be seen that upon turning the hand wheel 139 the sliding block 140 is moved upwardly or downwardly and through the hanger rod 141 moves the bracket 112 in a corresponding direction. This elevates or depresses the corresponding end of the angle bar 110 and consequently elevates the track and cutter bar supported thereby. The purpose of the opposing springs 143 and 147 is to permit the cutter bar assembly to yield slightly in its operation of cutting through the column of asphalt being discharged by the hopper. In order to balance the action of these springs, after the desired adjustment of the height of each end of the cutter bar has been obtained through the hand wheel 139, the hand wheel 145 is turned to relieve or increase the pressure exerted by the spring 147 downwardly upon the cutter bar assembly. The upper spring 147 is preferably heavier than the lower spring 143 to better resist the tendency of the cutter bar assembly to lift because of its compressing action caused by the inclined cutting edges of its teeth.

In surfacing a highway the pavement is laid in several strips and where one strip has been accurately laid it is desirable to be able to gage the height of the contiguous strip from the edge of the strip already laid so that the two strips form smooth continuations of one another and the joining of the two strips is effected without a seam. Also in laying the original strip it may be desirable or required that a form be used to pave from, such forms being in the nature of temporary rails accurately placed and leveled at the sides of the highway. Ordinarily two such forms are used, the present invention permitting of using one as a level gage surface. To permit of gaging the height of a strip being laid from the surface at the edge of a contiguous strip or from a single form, the dolly shown in Figs. 5 and 6 is employed. This dolly is in the form 45 of a bracket 150 carrying a pair of small rollers 151 which are adapted to ride upon the surface, near the edge, of a strip of pavement already laid or upon the form. The bracket 150 is provided with a pair of spaced vertical slots 152 and the dolly is secured by a pair of bolts 153 to a small angle bracket 154, this bracket in turn being secured to a small angle piece 155 welded on the rear face of the angle bar 110. The bolts 153 extend through the slots 152 so 55 that the position of the dolly relative to the angle bar 110 and hence the cutter bar assembly can be adjusted.

Cooperating in use with the dolly is a leveling device, illustrated in detail in Figs. 2 and 3, 60 and consisting of a swinging bracket 156 which is pivoted to the main frame of the paver to swing about an axis parallel with its line of movement on a pivot bolt 157. The leveling bracket 156 is preferably pivoted to the frame at 65 a point within convenient reach and observation from the operator's platform 48, such as the top rail of the rear wall 43 of the hopper 40. At its top the bracket 156 carries a bubble level 158 of any usual and well known type and at 70 its bottom this bracket carries a scale 159 which traverses a fixed indexing pointer 160. The bracket 156 is provided at its lower end with an arcuate slot through which a stud projects which carries a wing nut 161. It will be seen that 75 by loosening the wing nut 161 the bubble level

158 can be swung to any position relative to the hopper and upon tightening the wing nut 161 this relation can be maintained. Since the bubble level 158 extends transversely of the paver it will be seen that the bubble level will indicate any list of the machine and it will further be seen that by the adjustment of the bracket 156 the paver can be set to have any desired list, and this list maintained by watching the bubble in the bubble level and adjusting the elevation 10 of one end of the cutter bar to maintain this list.

Assuming that one strip of pavement or a single form has been accurately laid and it is desired to lay another strip against it, the dolly 15 150 is attached to the bracket 154 by means of the bolts 153. The height of the cutter bar is adjusted so that the teeth 103 engage the upper surface of the strip already laid and the bolts 153 are then tightened so that the dolly maintains this position of the cutter bar as the paver moves along. The opposite side of the cutter bar assembly is then adjusted, through the medium of the opposite hand wheel 139, to obtain the desired thickness of pavement on the opposite side of the strip being laid. The level indicator shown in Figs. 1, 2 and 3 is then adjusted so that the bubble is in the center of the bubble level 158. The paving thereupon proceeds with one side of the cutter bar gaged from 30 the strip of pavement already laid or gaged from the form. If the bubble in the bubble indicator deviates from the center the operator adjusts said other hand wheel 139 so as to elevate or drop the "free" edge of the strip being laid back 35 to the height desired and hence bring the bubble in the bubble level 158 back to the center. In this manner it will be seen that extreme accuracy can be obtained not only in working the strips together at their edges to form a smooth 40 continuation of one another, but also in accurately maintaining the level of the opposite side of the strip being laid.

In order to provide a square shoulder at the opposite side of the strip being laid an edger 45 plate 162 is employed at the opposite side of the paver. This edger plate is carried by a plate 163 which in turn is connected by a pair of bolts 164 with the link 111 that takes the thrust of the cutter bar assembly. The edger plate 162 is disposed under the teeth 103 of the cutter bar assembly, these teeth thereby travelling over the top of the edger plate and in close relation thereto so that the material being discharged from the hopper is pressed against the edger 55 plate by the teeth as they reciprocate and a square shoulder molded in the edge of the strip. It will be understood that when one strip is being laid an edger plate 162 will be provided at each side of the paver so that both edges of the 60 single strip will be provided with a square shoulder.

In order to heat the teeth of the cutter bar and thereby facilitate their action in cutting through the column of asphalt and stone being 65 discharged from the hopper and also to heat the material and provide a smooth ironed surface, the exhaust from the gas engine 50 is conducted to the space 165 formed between the channel 101, cutting plates 103 and spacer strips 102, the exhaust gases passing through this space and out through the open ends of this assembly. For this purpose an exhaust outlet 166 of the gas engine is connected to a flexible conduit 167 which in turn, as best shown in Figs. 4 and 15, 70 75

is connected to a fitting 168 mounted on the center of the flat channel 101. Under this fitting 168 the channel 101 is provided with an opening so that the exhaust gases can pass into the space or passage 165 and thence out through the opposite open ends thereof. By so employing the exhaust gases from the gas engine it has been found that the plates 103 of the cutter bar are maintained at a high temperature and their cutting action is facilitated and the material being discharged heated so as to secure a more compact texture.

It will be understood that while we have shown the cutter bar as being heated by the exhaust gases from the motor which propels the paver, this cutter bar could be heated by the hot water withdrawn from the cooling system of the motor or it could be heated by a separate heating device, such as a separate oil heater, blow torch or the like (not shown).

The paver is required to lay surfaces having different crowns ranging from a zero curvature, such as would be employed on a banked turn in a road, to a highly crowned road. To meet the different requirements in crowning a road the track for the cutter bar is adjustable as to curvature so that the cutter bar in reciprocating along this track will take a corresponding curvature and crown the road accordingly. It is one of the principal objects of this invention to provide a means for adjusting the curvature of the track by a single hand wheel or the like which is located on the operator's platform so that the curvature can be quickly and conveniently adjusted as conditions require, this being particularly important when the paver is merging a highly crowned road into a banked turn where no crowning is desired. To accomplish this the preferred means, best illustrated in Figs. 15-20, include a hand wheel 170 which is located within convenient reach of the operator's platform 48 and fast to a vertical shaft 171 which is journaled in a post 172. The lower end of the shaft 171 is splined, as indicated at 173, Fig. 17, this splined end of the shaft fitting into a universal joint 174. The other part of the universal joint 174 connects with a shaft 175 which is supported and journaled in a bearing provided on a bracket 176, this bracket being carried by the angle cross bar 110. On the lower end of the shaft 175 is fixed a bevelled pinion 177 which meshes with a bevel gear 178. This bevel gear is fast to a cross shaft 179, which shaft is journaled, at intervals, in bearings 180 (see Figs. 15 and 17), these bearings being secured to the angle cross bar 110. At intervals eccentrics 181 are mounted on the cross shaft 179 and each eccentric is housed within an eccentric housing 182, each housing forming the equivalent of an eccentric strap, so that as the eccentrics are turned the housings 182 are raised or lowered accordingly. Each eccentric housing 182 is connected by means of a rod 183 with the track 104 of the cutter bar assembly so that as the eccentric housings are moved up and down the track 104 is flexed accordingly. Preferably the upper end of each of the rods 183 is threaded into a boss 184 formed on the lower side of each eccentric housing 182 and is located in place by a nut 185.

In the paver shown the eccentrics 181 are shown as being five in number and spaced uniformly along the cutter bar assembly. The relative positions of the eccentrics are illustrated in Figs. 18 and 19 in which three of the eccentrics are shown, comprising the one center eccentric

and the two eccentrics on the one side of the paver. It will be noted that the rods 183 are of different lengths, the rods of the outermost eccentrics being the shortest and the rod of the center eccentric being the longest. The eccentrics are of uniform shape and when the track 104 is disposed on a straight line, as illustrated in Fig. 19, the salient portions of the outermost eccentrics extend vertically downward, the salient portion of the center eccentric extends horizontally and the intermediate eccentrics extend at an angle of 45°. As the shaft is turned in the direction of the arrow, shown in Fig. 19, the eccentrics gradually assume the position shown in Fig. 18, in which the outermost eccentrics are disposed at a 45° angle; the innermost eccentric is disposed at a 45° angle projecting upwardly and the intermediate eccentrics are horizontally disposed. In this position of the eccentrics, as shown in Fig. 18, the track 104 is curved to provide the maximum crown. In positions of the eccentric shaft intermediate that shown in Fig. 18 and that shown in Fig. 19, a lesser crown is, of course, obtained and it will therefore be seen that by turning the hand wheel 170 any desired crown can be provided in the roadway being laid inasmuch as curving the track 104 compels the teeth of the cutter bar assembly to traverse a similar curve and hence crown the road accordingly.

The hand wheel 170 is preferably provided with graduations, as indicated in Fig. 1, and a pointer 170a is stationarily mounted on the machine and is traversed by the graduations so that the crown which the cutter bar is set to provide can instantly be seen by the operator.

An alternative form of eccentrics is shown in Fig. 20, this view being a diagrammatic view similar to Fig. 19. In this form the eccentrics 181a are not of uniform throw, the center eccentric having a relatively great throw, the outermost eccentrics having the minimum throw and the intermediate eccentrics having an intermediate throw. The exact throw of the intermediate eccentric can be made to provide any condition of crowning which is desired and the length of the rods 183 are also adjusted to obtain the desired movement of the track. With the variable throw eccentric shown in Fig. 20 the salient portion of all of the eccentrics is directly downward when the track is in a straight line. Therefore upon turning the eccentric shaft in either direction the greater throw of the center eccentric will draw the track 104 up further at its center than the other eccentrics and since the outermost eccentrics have the smallest throw the track at its opposite ends will be drawn up a relatively small amount. Therefore by turning the eccentric shaft the eccentrics 181a will effect any desired crowning in the road up, of course to the maximum throw of the eccentrics.

After the roadway has been deposited and cut off to the proper grade a tamping mechanism on the paver tamps the roadway. This tamping mechanism is located immediately in rear of the cutter bar assembly and since the cutter bar assembly can be adjusted to provide any desired crown in the roadway the tamping mechanism is likewise rendered adjustable and consists of a plurality of small tampers, the relation of which can be adjusted to have the same curvature as the cutter bar assembly. To carry the tamping mechanism an angle bar 190 extends the full width of the paver immediately in rear of the angle bar 110 which carries the cutter bar as-

sembly. The angle bar 190 is mounted on springs, at its opposite ends. As shown in Fig. 4, each of the springs 191 is a compression spring and interposed between the top of the corresponding end of the angle bar 190 and a bracket 192 each of which is supported by a quick-lift device generally similar to the quick-lift device supporting the cutter bar assembly. A tie rod 193 limits the downward movement of each end 10 of the angle bar 190 so that these tie rods limit the downward movement of each end of the angle bar 190 but each end of the angle bar 190 is free to rise against the resistance of the springs 191. Preferably, also, a nut 194 is provided for adjusting the tension of the spring 191, as best shown in Fig. 4. The angle bar 190 carries, on its upper side, a plurality of spaced bearings 195 which support an adjusting shaft 196. This adjusting shaft is provided with a bevel gear 197 which is turned by a bevel gear 198 carried by the lower part of a universal 199. The other part of the universal 199 is splined, as indicated at 200 in Fig. 17, to a vertical shaft 201 which is driven by a gear 202 meshing with a gear 203 fast to the adjusting shaft 171. The adjusting shaft 171 is turned to adjust the crown of the cutter bar assembly and it will be seen that as this adjustment is effected a corresponding adjustment is made of the shaft 196 of the tamping mechanism. The shaft 196 carries a series of cams 205 which are provided in the same number and spaced in a similar manner to the cams 181 of the cutter bar assembly. As with the cams of the cutter bar assembly the cams 205 operate in eccentric housings 206 so that as the cam shaft 196 is turned the cams raise and lower these housings. Each of these housings is provided with a boss 207 into which is screwed a rod 208. The lower ends of the rods 40 208 connect with a flexible angle bar 209. This angle bar has a continuous lower web 210 and its vertical web 211 is disposed against the vertical face of the angle bar 190, as illustrated in Fig. 17, and is vertically slotted at intervals, as 45 illustrated at 212 in Fig. 16 so as to render the lower web freely flexible. The cams 205 are arranged in the same manner as the cams 181 for crowning the cutter bar assembly, i. e., either as shown in Figs. 18 and 19, or as shown in Fig. 20. 50 Therefore, as the cam shaft 196 is turned the cams increase or decrease the crown of the slotted flexible bar 209.

The tampers 215 are each carried by a pair of sliding rods 216 each of which is connected with 55 a head 217. A centering bushing 218 also surrounds each rod 216 and is preferably welded to the lower web 210 of the slotted angle bar 209. A compression spring 219 is interposed between each of the bushings 218 and the underside of the 60 corresponding head 217. Each head 217 is provided with a pair of upwardly extending ears 220 and between these ears a roller 221 is mounted in any suitable manner. Each roller 221 engages the face of a star-shaped cam wheel 222. The 65 projections of the star-shaped cam wheel are rounded so that as the star-shaped cam wheels 222 are turned the rods 216 are caused to reciprocate by reason of the engagement of the rollers 221 with the star-shaped cam wheels, the springs 70 219 acting in opposition to the salient portions of the star-shaped cam wheels to elevate the tampers. The star-shaped cam wheels 222 are provided in pairs, one pair being provided for each tamper 215. Each pair of star cam wheels 222 75 is connected by an integral sleeve 223 and each of

the sleeves 223 is journaled in a bearing 224, the bearings 224 being secured to the slotted vertical web 211 of the angle bar 209, as best shown in Figs. 17 and 21. Each pair of connected star wheels is provided at one end with a pair of lugs 5 225 which are adapted to fit in a pair of recesses 226 in the opposing end of the next succeeding pair of star wheels. Accordingly, the star wheels are connected to rotate in unison. In order to maintain the several star wheels in 10 proper axial relation a rod 227 extends axially through the center of all the star wheels, this rod being non-rotating and being connected at its ends to brackets at the ends of the angle bar 190, as best shown in Figs. 4 and 16. Power for turning 15 the several star wheels can be applied in any suitable manner from the gas engine 50. The several rollers 221 are also preferably continuously lubricated from a small cup 228 mounted on the upper side of each of the heads 217 and 20 containing a bath of oil in which the several rollers 221 rotate.

Means are also preferably provided for applying lubricant to each of the tampers 215 so that in addition to tamping the roadway they also 25 apply a small amount of lubricant during this operation and serve to prevent sticking of any of the roadway material to the tampers. For this purpose a plurality of lubricant supply lines 230 connect with a common lubricant supply (not 30 shown) and each of the lubricant supply lines 230 extend through the vertical slotted wall 212 of the flexible angle 209 and screws into the lower part of the corresponding bushing 218. A passage 231 connects the lubricant supply line with a passage 35 232 provided in each of the rods 216. The bottom plate 234 of each of the tampers 215 is provided with a plurality of openings 235 extending vertically therethrough, as best shown in Fig. 21, and the lubricant supply passages 232 in each 40 rod 216 discharge into the interior chamber 236 of each tamper 215 from which it passes out through the ports or passages 235 in the bottom plate of each tamper.

It is also desirable to provide a quick-lift device 45 at each end of the tamper assembly so that the opposite ends of the whole assembly can be quickly elevated in the same manner as the cutter bar assembly in passing over an intercepting road or the like and can be as quickly returned to the original adjusted position. To this end, each of the brackets 192 is connected to the main frame of the carriage by rivets 236 passing through vertical slots 237 in the bracket so that the bracket is free to rise and fall. The quick-lift device supporting the tamper assembly is 50 similar to the quick-lift device supporting the cutter bar assembly and the same reference numerals have therefore been employed and distinguished by the suffix *a*, the description of the cutter bar quick-lift applying to the tamper quick-lift and hence not being repeated, the lower end of the rod 144*a*, corresponding to the rod 144 of the cutter bar quick-lift being directly connected to ears 238 on the brackets 192, as best illustrated 55 in Fig. 16.

In the form of the invention shown in Figs. 1-21 the crown of both the cutter bar assembly and the tamper assembly is adjusted by turning the hand wheel 170. In place of a single adjustment for the crown of these assemblies the crown of the same can be adjusted by the modified form of mechanism shown in Fig. 22. In this form no cams are employed and the curvature of the track is adjusted by a plurality of rods 240 which are 60

connected at intervals to the track 104 in any suitable manner. Each of these rods 240 is threaded at its upper end and is connected to a rotatable nut 241, these nuts being carried by the angle 110 and each is turned by a vertical adjusting shaft 242. Each adjusting shaft 242 is connected at its upper end to a universal 243 which is splined as illustrated at 244 to a vertical shaft 245. The shafts 245 extend upwardly to a point within convenient reach of the operator on his platform 48 and is suitably supported in bearings provided in a bracket 246. The upper end of each adjusting rod 245 is squared, as illustrated at 247 so that by applying a wrench the operator can turn any of the shafts 245 and thereby turn the corresponding nuts 241 to raise and lower the corresponding screw rods 240. It will therefore be seen that by adjusting the several shafts 245 any desired crown can be obtained in the track 104 and consequently the curvature of the cutter bar assembly adjusted accordingly. The cutter bar assembly reciprocates on the track 104 in the same manner as in the preferred construction and therefore the same numerals have been employed 25 to designate similar parts.

In order to facilitate adjustment of the crown of the cutter bar and tamper assemblies, an indicator finger 248 is mounted in any suitable manner on the upper end of each of the shafts 30 245, this indicator finger traveling along an index scale 249 formed in the side of the bracket 246, as best illustrated in Fig. 23. It will be seen that this scale readily permits the operator to adjust each of the shafts 245 so as to obtain any desired 35 crown in the road.

Each of the shafts 245 carries a gear wheel 250 which meshes with a similar gear wheel 251, this gear wheel 251 being fast to a shaft 252, as best illustrated in Fig. 24. The lower end of the shaft 40 252 is splined (as at 253, Fig. 22), to one part of a universal 254, this universal driving a shaft 255 which is pinned to a nut 256. The nuts 256 are exactly similar to the nuts 241 which adjust the curvature of the track 104 and are threaded to 45 rods 257 the lower ends of which are suitably connected to the lower web of the flexible angle bar 209. This angle bar 209 is the same as that shown in the preferred form of the invention illustrated in Figs. 1-21 and carries an identical tamping 50 mechanism. Therefore the adjustment of the crown of the cutter bar assembly (by adjusting the curvature of the track 104) effects a similar adjustment of the slotted angle bar 209 and consequently adjusts the crown of the tamper 55 assembly.

In order to protect the rollers 34 and 35 which support the rear end of the paver against picking up pieces of the freshly laid roadway each roller is preferably lubricated by a lubricating device 60 which is preferably constructed as follows:

Above each roller 34 and 35 is mounted a small wooden roller 260. Each of the rollers 260 is provided with bearings 261 at its opposite ends which turn on a lubricant supply pipe 262. The lubricant supply pipe is in turn mounted in a pair of links 263 each of which is pivoted at its outer end to a bracket 264 on the main frame. Each of the wooden rollers 260 is covered with felt 265 and each felt covered roller is held in engagement with the corresponding main roller of the paver by a spring 266 which connects at one end with an arm 267 projecting upwardly from a cross bar 268, this cross bar connecting the opposite links 263 for each roller. The other end of the 75 spring 266 connects with an adjusting screw eye

269 which is adjusted by means of a wing nut 270 which bears against any suitable part of the main frame. Each of the lubricant pipes 262 is fed from a lubricant supply line 271 which is formed with a plurality of convolutions 272, as 5 illustrated in Fig. 1, to render it flexible and permit free movement of the roller 260. Each of these lubricant supply lines 271 connects to a common lubricant supply tank 273, as illustrated in Figs. 1 and 4. Within the roller 260 the lubricant pipe 262 is provided with a pair of discharge orifices 274 at its center and these orifices discharge lubricant into the center of the wooden roller 260 from which it is distributed through an axial bore to a plurality of radial passages 275. 15 By this means the felt covering 265 is kept constantly saturated with lubricant and from this covering the lubricant is transferred to the surface of the main roller 34 or 35, as the paver moves along. 20

As a final operation of the paver it is frequently desirable to entirely scarify that portion of the strip laid over which the rollers have passed. Thus, as the rollers 34 and 35 traverse the freshly laid strip they roll two stripes in the strip. Unless the entire strip is rolled immediately after the paver is passed these stripes may persist in the finished roadway and while the quality of the roadway is not in any way impaired the stripes are objectionable in point of appearance. Accordingly, the present paver scarifies that portion of the strip over which the rollers have passed so that the entire surface of the paved strip is roughened and when subsequently rolled, as by a steam roller, will result in a surface of uniform 30 35 appearance throughout.

Each of the scarifying devices includes a bottom plate 280 to which are removably secured a plurality of scarifying teeth 281 which project downwardly therefrom, as best illustrated in Figs. 7 40 and 10. This vertical plate is connected at its opposite ends to vertical angle bars 282 which are suitably braced by diagonals 283. The back of each of the vertical angle bars 282 is notched or serrated to provide a plurality of rearwardly facing teeth 284 and these teeth engage similar forwardly facing teeth 285 provided in vertical hanger bars 286. The vertical bars 282 and 286 are secured together by through bolts 287. The upper end of each of the hanger bars 286 is connected by a hinge pivot 288 with a transversely movable angle bar 289 which extends substantially the full width of the paver. It will be seen that by loosening the bolts 287 and adjusting the angle bars 282 upwardly or downwardly relative 45 to the hanger bars 286, the depth of penetration of the scarifying teeth can be adjusted as may be desired. The purpose of the hinge pivots 288 is to permit the scarifier frame to be moved from the operative position shown by full lines shown 50 in Figs. 4 and 7 to the inoperative position shown by dotted lines in Fig. 4. When the scarifier is in its operative position the rearward thrust against the teeth in traveling along the roadway is preferably taken by a flexible connecting member, such as the cable 290 shown in Fig. 4, which connects the bottom plate 280 of the scarifier with brackets 291 projecting downwardly from the main bearing brackets 36. The scarifier in rear of each roller 34 and 35 is connected, as 55 60 65 70 75 above described, to the movable angle bar 289. This angle bar is provided at its opposite ends with a pair of hangers 292, each of which hanger brackets 292 carries a pair of opposing rollers 293 and 294. Each roller 293 rides on the lower flange 75

295 of the cross channel 32 which forms a part of the main frame of the paver and the other roller 294 rides along the back of this channel 32. It will therefore be seen that the angle bar 289 is 5 compelled to travel along the channel 32. This angle bar 289 is reciprocated by means of a crank wheel 296 which is driven in any suitable manner by the gas engine 50 and carries a crank pin 297 driving a link 298, the other end of which connects with a bracket 299 which is secured to the 10 angle bar 289 of the scarifying apparatus. To guide the bracket 299 in its movement a guide bracket 300 is fixed to the rear side of the frame channel 32 and embraces the crank wheel 296 and 15 the bracket 299. It will therefore be seen that as the crank wheel 296 is rotated the angle bar 289 is reciprocated along the channel 32 and inasmuch as this angle bar 289 carries the scarifying apparatus, the teeth of the scarifiers are worked 20 transversely back and forth across the strips rolled by the rollers 34 and 35 and work this portion of the strip laid by the paver back into the same condition as that portion of the strip over which the rollers have not passed. The strip finished by the paver is therefore of uniform surface 25 texture and in condition for finishing by the usual steam roller or the like.

Operation

30 In the operation of the paver, assuming that a single strip is initially to be laid the paver can be started by first laying a sufficient amount of paving material of the desired height and thickness to receive and support the rear rollers 34 and 35 of the paver, the front or steering wheels 37, 38 of the paver riding along the surface which is to be paved. The operator thereupon adjusts the hand wheels 139 so as to adjust the height of the cutter bar at each side of the paver so as 40 to continue the probable elevation of the strip. Upon turning either hand wheel 139 to achieve this adjustment the slide 140 (see Fig. 14) is adjusted vertically which elevates or depresses the hanger rod 141 so as to raise or lower the 45 corresponding end of the bar 110 which carries the track 104 of the reciprocating cutter bar.

Thereafter the tension of the springs 101 (Fig. 4) which exert a downward pressure on the tamper assembly can be adjusted to secure the 50 desired tamping action. Further, if the strip of material being laid is to be much thicker at one side than at the other, the U-shaped washers 83 (see Fig. 11) which support either or both front corners of the main frame of the carriage on the front steering wheels 37 and 38 can be removed and the corner or corners elevated to provide the desired list before the U-shaped washers 83 are reinserted. It will be understood that minor variations in the thickness of the strip being laid can be obtained by adjustment of the 55 hand wheels 139 of the cutter bar assembly.

The operator then adjusts the level indicator (Fig. 3) so that the bubble is in the center of the bubble level 158.

60 The operator then brings the scarifier down to the operative position shown by full lines in Fig. 4 and secures the tension cable 290 in position. The operator also applies the edger plates 162 to both sides of the paver by attaching each to 65 the bars 111 and adjusts these edger plates so that the teeth 103 of the cutter bar just clear the top of the edger plates, as best shown in Fig. 4.

The operator can then adjust the crown of the 70 cutter bar assembly and also the crown of the

tamper assembly. To do this in the form of the invention shown in Figs. 1-21, the operator turns the wheel 170 (Fig. 15) which rotates the cam shaft 179 (Fig. 17) which rotates the cams 181 so as to elevate or depress the different portions 5 of the track 104 to provide the desired curvature thereof, the cams being set at different angles (Fig. 18) or having a variable throw (Fig. 20) so as to secure a uniform curvature of the track 104 in all positions of adjustment. Since the 10 cutter bar travels along this track 104 it will be seen that the cutter bar takes its curvature and hence grades the strip being laid to have a similar crown.

Turning the shaft 171 from the wheel 170 (Fig. 15 17) through the gears 203 and 202 also turns the cam shaft 196 of the tamper mechanism and these cams, which are formed and arranged similar to the cams 181 of the cutter bar assembly, adjust the curvature of the slotted angle bar 209 20 which carries the tampers 215. Therefore the curvature of the tamper bar assembly will be adjusted to have the same curvature as the cutter bar assembly.

The operator thereupon applies power to the 25 shaft 92 so as to operate the pinions 89 and, through the racks 88, draw the power closure gate 87 into its forward open position. The material in the hopper 40 is then free to pass out through the opening 47 in the bottom, the effective width of this opening being determined by 30 the number of plates 83 which are laid in the bottom of the hopper, this depending, of course, upon the width of strip which is desired to be laid.

The truck of paving material is then backed up between the front steering wheels 37 and 38 of the paver until its rear wheels engage the rollers 34 (Fig. 1). The operator of the truck thereupon elevates the body so that an amount 40 of paving material is deposited into the hopper 40. The operator thereupon applies power to the shaft 53 which rotates the shaft 64 and through the chain 67 drives the raker bar shaft 60 so as to start rotation of the raker bar 59 and spread 45 the material being dumped into the hopper uniformly over its entire width. Depending upon the consistency of the material to be laid the angularity of the blades carried by the raker bar shaft are adjusted to obtain the desired spreading 50 action of the raker bar. The operator then applies power to the crank wheel (not shown) which reciprocates the link 108 (Fig. 15) this in turn reciprocating the cutter bar assembly along the track 104. The operator also applies power 55 to the star-shaped cam wheels (Fig. 17) which in their rotation move the tampers 215 up and down. The operator also applies power to the crank wheel 296 (Fig. 7) which reciprocates the traveling angle bar 289 which carries the scarifiers in back of the rollers 34 and 35. It will also be understood that the operator turns on the lubricant supply lines 271 and 230 (Figs. 26 and 17, respectively) so as to supply lubricant to the wooden rollers 260 (Fig. 26) which apply the 60 lubricant to the rear rollers 34 and 35 and to the tampers 215 (Fig. 17).

The operator thereupon applies power to the rear rollers 34 and 35 and commences paving.

As the paver moves along, the material in the 70 hopper 40 drops through the slot 47 as a column and the teeth 103 of the cutter bar cut into this column and permit of the deposit of only enough material to form a strip which is graded and crowned by the cutter bar as it reciprocates along 75

its track 104. The reciprocation of the cutter bar works and smooths the strip being laid and further forces the material up against the edger plates 162 so as to mold the sides of the strip to have clean square shoulders. Further, the exhaust from the gas engine 58 is conducted through the flexible conduit 167 (Fig. 15) to the interior passage 165 of the cutter bar 100 (Fig. 17). This heats the cutter bar 100 so as to assist it in cutting through the column of material being discharged by the hopper and also to iron the surface of the strip being laid.

As the paver moves along, its front rollers 34 (Fig. 1) push the truck along so that the depositing of the material into the hopper 40 proceeds along with the movement of the paver in depositing the layer of paving material.

The front wheels 37 and 38 of the paver ride on the relatively rough subgrade and, of course, the front end of the paver necessarily rises and drops in accordance with irregularities in the subgrade. However, the rise and drop of the front end of the paver has a relatively small effect on the cutter bar 100 because this cutter bar is located near the rollers 34 and 35 which ride upon the strip of material being laid. Hence, even though the subgrade is relatively rough the strip of material laid will be quite smooth. Further, it is the practice to lay the material in two layers. Thus, after the roadway has been completely surfaced with the first layer the second layer is laid. It will be seen that the second layer will be extremely smooth and free from irregularities even though the subgrade was extremely rough because such irregularities would be only slightly reproduced in the first layer of material and almost completely eliminated when the second layer of material is laid over the first.

As the paver moves along the operator watches the bubble level 158 and if this level indicates that the paver has taken an undesired list the operator adjusts the corresponding hand wheel 139 (Fig. 14) so as to elevate or depress the corresponding end of the cutter bar 100 so as to bring the strip back to the proper transverse angle and hence bring the paver back to the desired lateral level in which position the bubble in the bubble indicator 158 will assume a central position.

Also, if in paving, the operator approaches a curve in the road he simultaneously slacks off on the hand wheel 170 so as to flatten the crown of the cutter bar 100 and the series of tampers and also adjusts one or the other of the hand wheels 139 so as to elevate one side of the cutter bar assembly. Such adjustment provides the desired bank in the roadway at the curve. Of course, when the curve is passed the operator restores the crown in the cutter bar assembly and restores the elevation of the ends of the cutter bar assembly to continue paving as before the curve was encountered.

As the paver moves along the tampers 215 move up and down and tamp the strip laid by the cutter bar. As the rollers 34 and 35 pass over this strip the stripes which are formed by the rollers in the strip are eradicated by the teeth 281 (Fig. 7) of the scarifiers which are reciprocated back and forth across the stripes by the crank wheel 296.

When an intersecting road is encountered the operator applies power to the shaft 92 (Fig. 4) so as to close the power cutoff closure 87. This holds the material in the hopper 40 while the paver is driven across the assumed intersecting

paved road. Thereupon the operator lifts the scarifier to the dotted line position shown in Fig. 4 by uncoupling the cables 290 and also lifts the entire cutter bar assembly and edger plates 162 by the quick-lift device shown in Figs. 13 and 14. To operate each quick-lift device the operator kicks out the locking plates 132, steps upon the treadle 124 so as to release the tooth 120 from the locking notch 131 and seizes the lever 126 together with the small gripping lever 130 10 and draws the two rearwardly. This causes the dog 127 to engage the teeth of the ratchet 119 and rotate the ratchet wheel. He then steps off the treadle 124 which permits the tooth 120 to act as a holding dog in the continued reciprocation of the hand lever 126. The turning of the ratchet wheel 119 through this reciprocation of the hand wheel lever 126 turns the shaft 115, thereby lifting the cranks 117 and elevating both brackets 113 which carry the adjusting mechanism for the opposite ends of the cutter bar assembly. Hence it will be seen that the cutter bar is quickly lifted so as not to be injured in traversing the assumed intersecting road and it will also be seen that the edger plates 162 are 25 likewise elevated since they are carried on the same bar 111 (Fig. 4) which is secured to and takes the rearward thrust of the cutter bar. In a like manner the operator operates the quick-lift for the tamper assembly in the same manner 30 as the quick-lift for the cutter bar assembly.

When the intersecting road has been passed the scarifier is replaced; the operation of the quick-lift device (Figs. 13 and 14) is reversed so as to restore the cutter bar to its original operating position and the power closure 87 is opened so as to start the flow of material from the hopper to the cutter bar and the paving proceeds as previously described.

When one strip has been laid the next strip is 40 laid against the first strip. To do this the edger plate 162 at that side of the paver which travels along the edge of the strip already laid is removed and the bracket 150 (Fig. 5) of the dolly is substituted for this edger plate. This dolly has 45 rollers which are arranged to ride on the edge of the strip already laid and the elevation of the cutter bar assembly relative to those rollers is adjusted (by the holding bolts 153) so that the cutter bar assembly works into the surface of 50 the strip already laid and hence provides a seam- less joint. It will be seen that by laying the first strip with extreme care the dolly shown in Fig. 5 permits this strip to be used as a gage for the strip being laid against the first strip, this dolly 55 supporting the corresponding end of the cutter bar assembly. The operator thereupon adjusts the hand wheel 139 at the opposite side of the paver so as to provide the desired thickness of pavement at that side and also adjusts the level 60 indicator 158 so that the bubble of this indicator is in the center as long as this desired list of the paver is maintained. If the paver, in paving, departs from this desired list it will immediately 65 show in the bubble indicator 158 and the operator can adjust the said outer hand wheel 139 so as to elevate or depress the outer end of the cutter bar assembly up or down to restore the paver to the desired position and the bubble in the 70 bubble indicator to the center. It will therefore be seen that once a strip has been laid succeeding strips can be laid with extreme accuracy by using the first strip as a master gage and by observing the bubble indicator 158 so as to insure a uniform 75

continuation from the first strip in laying the second strip.

It will be understood that when the dolly is used in gaging the strip being laid from either a previously laid strip or from a form, the end of the cutter bar supported by the dolly must be free to raise and lower or float with the dolly. To free that end of the cutter bar supported by the dolly, the operator turns the hand wheel 146 to relieve the downward pressure of the spring 143 (see Figs. 13 and 14) and relieves the cutter bar from the downward pressure of this spring and leaves it free to rise and follow the dolly.

It will also be understood, as previously pointed out, that the dolly can be used to gage from a single form by laying the form and having the dolly traverse the form.

From the foregoing it will be seen that the present invention provides an extremely versatile paver which will handle such difficult materials as asphalt and aggregate mixes and, with or without the use of forms, will resurface an extremely rough subgrade with a smooth finished layer. Furthermore, with the paver shown the material deposited can be laid with any desired crown and the paver permits of merging this crown into a banked curve and vice versa with little difficulty. The pavement laid by the paver can also be tamped so as to have a compact texture. Provision is made for scarifying the strip laid behind the rollers so that the roadway can be so laid as to be free from stripes which might persist due to the passing of the rollers leaving part of the strip rolled and part unrolled. It is also apparent that adequate provision is made for lubricating the rollers and tampers so as to prevent sticking of any of the surfacing material to the same and by the application of heat to the cutter bar the waste heat of the exhaust gases is usefully employed to assist the cutter bar in cutting through the column of material discharged by the hopper and also to provide an ironed finish upon the roadway. It will also be seen that by the use of the dolly shown in Fig. 5, and especially in combination with the level indicator shown in Fig. 3, an extremely smooth and evenly crowned roadway can be obtained with comparatively little difficulty. The paver as a whole is also extremely simple in construction and operation, considering its versatility and the various functions which it performs and it contains no parts which are liable to get out of order in operation, a condition which is to be especially avoided in pavers of this character since the operation of the paver is synchronized with the flow of materials to it and other operations upon the roadway.

We claim as our invention:

1. In a road paver of the character described, a carriage, a pair of vertical bearings at the front end of said carriage, a steering spindle journaled in each of said bearings, a steering knuckle fast to each spindle, a steering wheel carried by each of said steering knuckles and supporting the front end of said carriage, means on said carriage for turning said steering knuckles to steer said wheels, means for independently adjusting the elevation of each of said steering bearings relative to its steering spindle, said last adjusting means each comprising a horseshoe shaped washer adapted to bear against the underside of the corresponding steering bearing and engage one of a series of vertically spaced horizontal annular grooves provided in the corresponding spindle, means for rollably supporting

the rear end of said carriage, a hopper carried by said carriage and arranged to deposit paving material on the surface to be paved and means associated with said hopper for grading the material discharged from the hopper. 5

2. A road spreader of the character described, comprising a carriage, a hopper mounted on said carriage and having an elongated bottom discharge opening arranged transversely of the line of movement of said carriage, horizontal ledges 10 arranged in the lower part of said hopper on opposite sides of and immediately adjacent said opening and means for blocking off a portion of said hopper to vary the width of the strip of pavement deposited by said hopper, comprising a series of horizontal plates adapted to be arranged side by side in tandem relation and each supported at its opposite ends on said ledges to block off the corresponding part of said opening. 15

3. In a paver of the character described, a carriage adapted to traverse the surface to be paved, a cutter bar holder carried by said carriage, a reciprocating cutter bar carried by said holder, means for depositing the paving material on the surface to be paved in advance of said cutter bar and means for adjustably raising and lowering said cutter bar holder relative to said carriage comprising a vertical rod, spring means connecting said rod to the underside of said holder, means for raising and lowering said rod relative to said carriage, a member adjustably connected to said rod for vertical movement relative thereto and spring means interposed between said last member and an upper 25 side of said cutter bar holder.

4. In a paver of the character described, a carriage adapted to traverse the surface to be paved, a cutter bar holder carried by said carriage, a reciprocating cutter bar carried by said holder, means for depositing the paving material on the surface to be paved in advance of said cutter bar and means for adjustably raising and lowering said cutter bar holder relative to said carriage comprising a vertical rod, a relatively light compression spring connecting the lower end of said rod with the underside of the cutter bar holder, means for raising and lowering said rod relative to said carriage, a tube surrounding the upper end of said rod and having threaded engagement therewith, means for turning said tube relative to said rod and a relatively heavy compression spring interposed between the lower end of said tube and an upper side of said cutter bar holder and working in opposition to said relatively light spring. 45

5. In a paver of the character described, a carriage adapted to traverse the surface to be paved, a cutter bar holder carried by said carriage, a reciprocating cutter bar carried by said holder, means for depositing the paving material on the surface to be paved in advance of said cutter bar, a bracket carried by said carriage, means adjustably connecting said bracket and cutter bar holder and permitting of adjustably raising and lowering said cutter bar holder relative to said bracket and an independent quick lift means connecting said bracket with said carriage, said quick lift means permitting said bracket to be quickly elevated and quickly restored to its initial position thereby to permit of quickly elevating the cutter bar without losing its adjustment. 60

6. In a paver of the character described, a carriage adapted to traverse the surface to be 70

75

- 5 paved, a cutter bar holder carried by said carriage, a reciprocating cutter bar carried by said holder, means for depositing the paving material on the surface to be paved in advance of said cutter bar, a bracket carried by said carriage, means adjustably connecting said bracket and cutter bar holder and permitting of adjustably raising and lowering said cutter bar holder relative to said bracket and an independent quick lift means connecting said bracket with said carriage and comprising a crank arm mounted on said carriage, means connecting the outer end of said crank arm with said bracket and means on the carriage for rotating said crank arm, the 10 rotation of said crank arm quickly elevating and depressing said bracket thereby permitting of quickly elevating and restoring said cutter bar without losing its adjustment.
7. In a paver of the character described, a carriage adapted to traverse the surface to be paved, a cutter bar holder carried by said carriage, a reciprocating cutter bar carried by said holder, means for depositing the paving material on the surface to be paved in advance of said cutter 15 bar, a bracket carried by said carriage, means adjustably connecting said bracket and cutter bar holder and permitting of adjustably raising and lowering said cutter bar holder relative to said bracket and quick lift means connecting said bracket with said carriage and comprising a rotatable shaft mounted on said carriage, a crank arm on said shaft, means connecting the outer end of said crank arm with said bracket, a ratchet wheel on said shaft and a lever, dog and 20 detent means mounted on said carriage and co-acting with said ratchet wheel to rotate said crank arm and quickly raise or lower said bracket thereby permitting of quickly elevating and restoring said cutter bar without losing its adjustment.
8. In a paver of the character described, a carriage adapted to traverse the surface to be paved, an elongated cutter bar holder carried by said carriage, a reciprocating cutter bar carried by 25 said holder and arranged longitudinally thereof, means for depositing the paving material on the surface to be paved in advance of said cutter bar, lifting means carried by said carriage and extending parallel with said cutter bar holder to provide a quick lift mechanism for said cutter bar, independent means adjustably connecting each end of said cutter bar holder with the corresponding end of said lifting means to permit of independently adjusting the elevation of said 30 cutter bar holder relative to said lifting means and means for actuating said lifting means to simultaneously elevate both ends of said cutter bar holder.
9. In a paver of the character described, a carriage adapted to traverse the surface to be paved, an elongated cutter bar operatively connected to said carriage and extending transversely of the direction of movement of said carriage, and arranged to level paving material deposited on the 35 surface to be paved, means for supporting one end of said cutter bar on the surface to be paved and means for supporting the other end of said cutter bar on a prelaid surface parallel to which the strip being laid is being deposited thereby to insure the formation of a smooth surface by said cutter bar gaged from said prelaid surface said last supporting means comprising a dolly having a supporting roller and removably connected with the corresponding end of said cutter bar.
- 75 10. In a paver of the character described, a car-

riage adapted to traverse the surface to be paved, an elongated cutter bar operatively connected to said carriage and extending transversely of the direction of movement of said carriage and arranged to level paving material deposited on the surface to be paved, means for supporting one end of said cutter bar on the surface to be paved and means for supporting the other end of said cutter bar on a prelaid surface parallel to which the strip being laid is being deposited thereby to insure the formation of a smooth surface gaged from said prelaid surface, said last supporting means comprising a dolly having a supporting roller and removably connected with the corresponding end of the cutter bar.

11. In a paver of the character described, a carriage adapted to traverse the surface to be paved, means for depositing the paving material on the surface to be paved, a cutter bar holder operatively associated with and carried along with said carriage, an elongated, lengthwise reciprocating, cutter bar carried by said cutter bar holder and arranged to grade the deposited material, means moving with said carriage for supporting one end of said cutter bar holder to follow, in general, the undulations of the surface to be paved and means for supporting the other end of said cutter bar holder on a prelaid surface parallel with which the strip being laid is being deposited thereby to insure the formation of a smooth surface by said cutter bar gaged from said prelaid surface, said last supporting means comprising a dolly and means for attaching said dolly to the corresponding end of said cutter bar holder.

12. In a paver of the character described, a carriage adapted to traverse the surface to be paved, an elongated cutter bar operatively connected to said carriage and extending transversely of the direction of movement of said carriage and arranged to level the paving material deposited on the surface to be paved, means for reciprocating said cutter bar transversely of the line of movement of said carriage, means on said carriage for adjusting the elevation of said cutter bar relative to the surface to be paved, an internal combustion engine for propelling said carriage and means for internally heating said cutter bar.

13. In a paver of the character described, a carriage adapted to traverse the surface to be paved, an elongated cutter bar operatively connected to said carriage and extending transversely of the direction of movement of said carriage and arranged to level the paving material deposited on the surface to be paved, an internal combustion engine for propelling said carriage, means for internally heating said cutter bar through heat derived from the combustion of the fuel in said engine and means for reciprocating said cutter bar through power derived from said engine.

14. In a paver of the character described, a carriage adapted to traverse the surface to be paved, an elongated cutter bar operatively connected with said carriage and extending transversely of the direction of movement of said carriage, means for reciprocating said cutter bar, said cutter bar comprising an upper elongated plate, side spacer bars depending from the longitudinal edges of said plate, sections secured across the bottoms of said spacer bars and projecting forwardly to form teeth which level the paving material deposited on the surface to be paved and means in the space between said upper plate, spacer bars and sections for heating said cutter bar.

15. In a paver of the character described, a car-

riage adapted to traverse the surface to be paved, a guide track extending transversely of said carriage, a cutter bar mounted for longitudinal reciprocatory movement along said track and arranged to level paving material deposited on the surface to be paved, a plurality of movable members spaced along said track and operating to crown said track to a greater or less degree, and a single operating member for simultaneously actuating all 10 of said movable members to provide any desired crown in said track.

16. In a paver of the character described, a carriage adapted to traverse the surface to be paved, means for depositing the paving material on the 15 surface to be paved, a cutter bar holder operatively associated with and carried along with said carriage, a guide track on said cutter bar holder extending transversely of the direction of movement of said carriage, a cutter bar mounted for 20 longitudinal reciprocatory movement along said track and arranged to level the paving material deposited on the surface to be paved, a plurality of movable members mounted on said cutter bar holder in spaced relation along said track and operatively connected with said track to crown said track to a greater or less degree upon being moved 25 in unison and a single operating member for simultaneously actuating all of said movable members to provide any desired crown in the track.

30 17. In a paver of the character described, a carriage adapted to traverse the surface to be paved, a hopper on said carriage and having an elongated bottom opening through which the paving material is discharged on the surface to be paved, a

cutter bar holder associated with and carried along with said carriage, a track on said cutter bar holder and extending transversely of the direction of movement of said carriage, a cutter bar mounted for longitudinal reciprocatory movement along said track and arranged to level the paving material discharged through said hopper opening, adjusting means operatively connecting said cutter bar holder and track at spaced intervals and operating to flex said track relative to 10 said cutter bar holder and means adjacent the upper part of said hopper for actuating said last named means.

18. In a paver of the character described, a carriage adapted to traverse the surface to be paved, 15 a cutter bar operatively connected to and movable with said carriage for leveling paving material deposited on the surface to be paved, means for adjustably flexing said cutter bar to provide any 20 desired crown therein, a crown bar extending 25 across said carriage in rear of said cutter bar and operatively connected with said carriage, an angle bar below said cross bar and having a continuous lower web and a slotted vertical web whereby said angle bar is vertically flexible, a cross 30 shaft journaled on said cross bar, cams on said cross shaft at spaced intervals, means connecting each cam with said angle bar, said cams being so formed that upon turning said shaft, said angle bar is flexed to assume the desired crown and a plurality of vertically reciprocating tampers carried by said angle bar.
